UNITED STATES PATENT OFFICE.

CHARLES HALL, OF NEW YORK, N. Y., AND JOHN YOUNG, OF NEWARK, NEW JERSEY, ASSIGNORS TO SAID CHARLES HALL.

BOLT-MACHINE.

SPECIFICATION forming part of Letters Patent No. 340,306, dated April 20, 1886.

Application filed December 11, 1885. Serial No. 185,336. (No model.)

To all whom it may concern:

Be it known that we, CHARLES HALL, of the city, county, and State of New York, and JOHN YOUNG, of Newark, in the county of 5 Essex and State of New Jersey, have invented an Improvement in Bolt-Machines, of which the following is a specification.

This invention is especially applicable to bolt-machines of the character represented in 10 Letters Patent No. 317,642, granted to us May 12, 1885, and we have described the said invention with special reference to the said machine, but we do not limit our invention to this machine, as the present improvements 15 are available with any bolt-machine in which there are dies that open and close to grasp the bolt-rod and to forge up the head of the bolt by a lateral pressure in addition to the upsetting action of a plunger.

20 In a machine for making carriage-bolts jaws have been employed for holding the bolt while the conical head and squared shank are forged upon the same, and automatic mechanism has been used for partially revolving the bolt when 25 the grasping-jaws are open. In our machine the bolt-head is polygonal and the sides of the head are forged by the dies as the jaws are closed to grasp the bolt previous to the plunger striking the top of the head. We 30 have discovered that in addition to the automatic turning of the bolt as the polygonal head is forged, it is necessary to give an endwise motion to the bolt to insure a proper forging action and to supply the metal necessary to 35 make a perfect head.

In bolt-machines of the character to which our improvements relate, the tools that hold the heated rod and form the sides of the head are grooved for the rod itself and made with shoulders and sides at the forward ends, between 40 which the head is forged up. When the heated blank is placed between these tools, the end projects and a plunger is brought up powerfully to upset the metal and spread it between 45 the shoulders of the tools. Usually the metal spreads in the direction of the opening in the tools wider than the head; hence such tools as they close the next time compress the sides of the head, because the bolt between the blows 50 has received either a quarter or a sixth of a revolution. This manner of forging bolts with

square or polygonal heads and the machines for the same are well known.

In our improvement the holding-dies are opened, and at the same time the rotating 55 mechanism is opened by a treadle, in order that the heated blank or bolt rod may be inserted, the holding-dies are closed, the plunger brought up against the end of the bolt to upset the same, the holding-jaws open, and the 60 automatic mechanism grasps and moves the bolt slightly endwise and rotates the bolt forty-five degrees, sixty degrees, or ninety degrees for eight-sided, six-sided, and four-sided heads. The holding-dies then close and press 65 upon the sides of the head, to forge up the same, and at the same time hold the bolt, and then the plunger strikes a second blow, &c.

By this improvement we are enabled to effect the forging of the head with greater 70 accuracy, and we avoid the risk of injury to the bolt by the lack of skill in the workman who feeds in the bolt-rod.

In the drawings, Figure 1 is a plan view of our improvement and so much of the machine shown in the said Patent No. 317,642 as is necessary to understand the connection of the improvement with the same. Fig. 2 is an end view of the improved mechanism for rotating the bolt, the frame being shown 80 as broken open and the holding-dies removed, but their positions indicated by dotted lines; Fig. 3, an elevation, Fig. 4 a plan view, and Fig. 5 an end view, of the arm and adjustable crank-pin for varying the extent of motion 85 given to the fingers that revolve the bolt-rod. Fig. 6 illustrates a modification in the devices for rotating the bolt-rod. Fig. 7 is a diagram of a modification of the rotating mechanism, and Fig. 8 shows a square-headed bolt as 90 forged by this machine.

The holding-jaws G' H² and the upsetting-plunger O are similar to those shown in our aforesaid patent, and the plunger O receives its motion from a cam, of any desired character, upon the shaft D. Upon the shaft D is a cam, D', with projecting inclined segmental ribs 2 and 3, that are properly shaped to give motion to the parts, as hereinafter described. Upon the frame A is a stock, B', through 100 which passes a tubular shaft, b, and within this is a shaft, a. Upon one end of the shaft a

is an arm, a' , that projects so that its end rests against the cam-surface 2, and upon the tubular shaft b is an arm, b' , which engages the cam-surface 3. At the other end of the shaft a is a crank-arm, a^2 , which is connected by a link, a^3 , to a crank-arm, d , on a tubular shaft, d' , that is supported in a bearing, d^2 , screwed to the frame of the machine. Within this tubular shaft d' is a shaft, e , one end of which is made with a screw-thread, e^2 , within the stationary bearing e^3 , that is screwed to the frame. Upon this shaft e is a cross-head, f , to which are hinged the fingers g g' , that extend upwardly at the back ends of the holding-jaws G' H^2 between said jaws and the frame of the machine. The finger g' extends below the cross-head f and hinge 4 and terminates preferably with a roller, 5, and there is a spring, h , at one side of this roller, and said spring extends downwardly and is fastened to the frame of the machine. This spring, acting on the roller 5, tends to press the finger g' upon the bolt-rod I and hold the same between the fingers g g' . It will now be evident that if the shaft e is partially rotated the finger g will be moved up by the cross-head f , and at the same time the finger g' will be moved down and the bolt-rod I will be partly rotated. I provide for varying the extent of motion given to the shaft e , as hereinafter described, so that the fingers g g' will be moved a proper distance, according to the size of the bolt made use of, and according to the number of degrees of rotation to be given to the bolt-rod in making four, six, or eight sided heads, and I arrange mechanism for relieving the pressure of the spring h upon the roller 5, in order that the pressure of the fingers upon the bolt-rod may be lessened or removed when the shaft e or cross-head f are moved in the other direction.

There is a crank-arm, d^3 , upon the tubular shaft d' , adjacent to the roller 5, and the spring h is wide enough for this crank-arm d^3 to press against the same and relieve the roller 5 from the pressure of the spring h , and the sizes and proportions of the parts are such that the cam 2, acting upon the arm x' , turns the same and the shaft a , and, by the crank a^2 and link a^3 , moves the crank-arm d , tubular shaft d' , and arm d^2 , to relieve the pressure of the spring h upon the roller 5 at the time the clamping-jaws G' H^2 are holding the bolt-rod I, and at this same time the cam 3 acts upon the arm h' and intermediate mechanism to partially rotate the shaft e and cross-head f , to move the fingers g g' at the sides of the bolt-rod I without turning the same.

In the connections between the tubular shaft b and the shaft e , I provide means for adjusting the extent of motion that the cam 3 gives to the fingers g g' , and with this object in view I connect to the back end of the shaft e a crank, k , and a connecting-rod, k' , to a crank-pin, l , that is provided with a base that slides in the ways l^2 upon a crank-arm, L , that is connected to the tubular shaft b . There is a

screw, l^3 , passing through a flange upon the crank L and through the base of the crank-pin l . By rotating this screw l^3 the crank-pin l is adjusted so as to be nearer to or farther from the shaft b , and hence more or less motion will be given by the crank L and connecting-rod k' to the crank k and shaft e . It is preferable to mark upon the ways l^2 divisions to be made use of in setting the crank-pin l , the divisions on one of the ways being adapted to six-sided bolt-heads and those on the other ways being adapted to four and eight-sided bolt-heads. These divisions should be marked so as to indicate the size of bolt-rod, as illustrated in Fig. 3, so that when the index upon the base of the crank-pin l is moved to the division indicated the parts will be set to a rod of the size denoted, and the motion will be forty-five degrees, sixty degrees, or ninety degrees, according to which scale is made use of upon the ways l^2 .

The spring R^2 is between an arm that extends from the crank L and the frame of the machine. It tends to keep the cam-arm a' toward and against the cam 2, and to partially rotate the shaft e in the opposite direction to the movement given by the cam 2.

As the jaw H^2 opens, it is necessary that the bolt-rod be moved slightly away from the semicircular recess in the holding-die that is within the jaw G' , in order that it may be free to turn. To effect this I make use of a hook, n , hinged to the finger g , and there is a latch-piece, n' , upon the jaw H^2 , so that as the jaw H^2 opens the latch-piece n' , acting upon the hook n , draws the fingers g g' out of the recess in the jaw G' , to move the bolt-rod I. At this moment the shaft e and cross-head f are partly rotated and the finger g' carried up and the finger g brought down, and the bolt-rod I receives its partial rotation.

As before mentioned, there is a screw-thread, e' , near one end of the shaft e , within the bearing e^3 , and the direction of rotation and the angle of the screw-thread are such that when the shaft e receives the partial rotation aforesaid in rotating the bolt-rod, the shaft e , and fingers g g' , and bolt-rod I are moved by the action of the screw-thread, to carry the heads of the bolt toward the upsetting-die O a sufficient distance to clear the bolt-head from the portions of the jaws G' H^2 , that form the shoulders at the under side of the bolt-head, and thereby supply sufficient of the bolt-rod to fill out and make perfect the head of the bolt.

The dies, adapted to grasp the bolt-rod and to form the head, usually called the "tools," that are placed in the holding-jaws G' H^2 , are removable, so as to be adapted to the grasping of bolts of different sizes. It is to be understood that the head of the bolt is formed between the offsets in the tools within the jaws G' H^2 by the pressure of the plunger O, as usual in bolt-machines. I place upon the jaw G' a block with a screw, o' , passing through it and acting against the back of the finger g , in order that the face of said finger may occupy

the proper position adjacent to the bolt-rod I when grasped by the tools in the jaws G' H'.

I make use of a contractile helical spring, r, between the under part of the hook n and the 5 jaw g', which spring tends to open the jaws g' for the insertion of the bolt-rod I, when the pressure of the spring h upon the roller 5 is taken off, and at the same time this spring r draws down the hook n toward the latch n'.

10 It is necessary to provide means for throwing out of action the fingers g' by the workman in cases where the bolt-rod is to remain without being rotated for one or more blows upon the head and for allowing for the entrance of the heated rod or for removing the headed blank. To effect this object, I make use of a bell-crank lever pivoted at S', one arm, S, of which passes up near to the spring h, so that by it the spring h may be pushed back out of 15 action. The other arm, S', of this lever is hinged to a slide, S', the upper end of which slide is guided by a loop upon the side of the arm carrying the jaw H', and the upper end is adjacent to the hook n. This lever S S' is 20 controlled by a treadle of any suitable character, so that the workman by depressing the treadle with his foot raises the arm S' and slide-bar S', lifting the hook n out of the way of the latch n', and at the same time moving 25 the arm S of the bent lever and pressing back the spring h from the roller 5, thus allowing the spring r to open the fingers and hold them out of the way of the bolt-rod.

In Fig. 6 we have illustrated a progressive 30 rotary device for moving the bolt-rod, the rollers g' acting in place of the fingers in rotating the bolt-rod, and to these rollers a progressive movement is communicated by a wheel and ratchet and pawl; but we prefer the 35 devices shown in Figs. 1 and 2, because we are able to give to the bolt-rod an end movement simultaneously with the rotary movement.

In Fig. 6 the arm A' has an eye that is loose 40 upon the shaft A', and this arm A' is provided 45 with a stud, to which a spring, B', is connected at one end, the other end of the said spring being attached to a portion of the swinging jaw H', so that as the said jaw H' opens the arm A' will be swung upon the shaft A' 50 until it is arrested by the screw-stop B'. Upon this arm A' is a projection and stud carrying the roller g, and there is a gear-wheel, K', upon the shaft A', gearing into a wheel, K', upon the stud I', which wheel K' 55 gears into pinions adjacent to and connected with the respective wheels g'. The wheel g' is upon a lever-arm, L', having the stud I' as its pivot, and the spring L' tends to press the roller g' away from the roller g when unacted 60 upon by the treadle and connection, and there is a small wheel, N', upon an arm, N', pivoted at N' to the arm A'. Upon this wheel N' the bolt-rod I rests, and it is also between the wheels g'. There is a movable pin at O', 65 passing through holes in the arms A' and N', the object of this wheel N' and adjustment being to adapt the apparatus to bolt-rods of dif-

ferent sizes, for when a bolt-rod of a large size is being operated upon the wheel N' and its arm N' is lowered and the pin O' inserted in 70 its appropriate holes. When the apparatus is to be used with a small bolt-rod, the pin O' is withdrawn, and the wheel N' and arm N' raised to the proper point, and the pin reinserted in its appropriate holes, so that the axis 75 of the bolt-rod may always occupy the proper position.

Upon the shaft A' is an arm, P', with a roller, P', at the end, that passes in between the stationary bracket P' and the cylindrical 80 flange P' upon the wheel K', and there is an adjusting-screw, Q', passing through a lug on the arm A' and acting against a toe upon the arm P'.

The operation of these parts is as follows: 85 As the jaw H' is opened, the spring B' swings the arm A' upon the shaft A', and at this moment the roller P', wedging in between the bracket P' and the cylindrical flange P' of the wheel K', holds said wheel K' stationary, and 90 the wheel K' is partly rotated by being carried with the arm A', and in so doing the wheels g' are rotated and turn the bolt-rod I, and the extent of this turning motion is regulated by the stop-screw B'. As the jaw 95 H' closes, the whole of the parts swing upon the shaft A', the wheel K' and its cylindrical flange P' moving with the other parts, and the weight of the arm P' causes the roller P' to remain in contact with the bracket P' until the screw Q' acts to lift the arm P' and its roller P', when the end of said screw Q' comes into contact with the toe of the arm A'.

In machines that have heretofore been made for forging carriage-bolts the head is circular, 105 and in some machines of this character devices have been proposed for turning the bolt-rod. Our present improvements are to be distinguished from this class of machines, because in our machine the dies are made with recesses for the bolt-rod, in which said rod is grasped when the dies are closed, and there are offsets with flat surfaces that forge up the edges of the bolt-head, and the bolt-head is not formed within a recess, but by compression laterally by the flat surfaces of the dies, 110 as well as by the spreading action of the plunger, and the number of sides formed upon the polygonal head depends upon the number of degrees in the rotary movement given to the 115 bolt-rod by the automatic mechanism, so that the bolt-head is forged accurately with either four, six, or eight sides. This feature is not found in the automatic feeding-machines heretofore made.

120 We claim as our invention—

1. The combination, with jaws for holding the bolt-rod I and for forging the sides of the bolt-head, of automatic mechanism, substantially as specified, for giving to the bolt a partial rotation, while the holding and forging jaws are opened, substantially as set forth.

2. The combination, with the holding-jaws, dies for forging up the sides of the bolt-head,

- and plunger for pressing upon the bolt-head, of fingers at opposite sides of the bolt-rod, springs for pressing the fingers toward each other, and mechanism, substantially as specified, for moving the fingers and partially rotating the bolt at the time the holding-jaws are opened, substantially as specified.
3. The combination, with dies for holding the bolt-rod and for forging the head, of fingers $g g'$, one at each side of the bolt-rod, cross-head f , to which the fingers are attached, the shaft e , and mechanism, substantially as specified, for giving to the same a partial rotary movement, as set forth.
- 15 4. The combination, with the holding and forging dies in a bolt-machine, of the fingers $g g'$, cross-head f , shaft e , having a screw near one end, and mechanism, substantially as specified, for giving to the said shaft e a partial rotary movement to turn the bolt-rod and to move it endwise, substantially as specified.
- 25 5. The combination, with the holding and forging dies in a bolt-machine, of the fingers $g g'$, cross-head f , to which they are pivoted, shaft e , and spring h , that acts to press the fingers upon the bolt-rod, and mechanism, substantially as specified, for partially rotating the shaft e .
- 30 6. The combination, with the holding and forging dies in a bolt-machine, of the fingers $g g'$, a spring to cause the pressure of the fingers upon the bolt-rod, a treadle, and connections for throwing out of action the said spring, and mechanism, substantially as specified, for moving the fingers in opposite directions, substantially as set forth.
- 35 7. The combination, with the holding and forging dies in a bolt-machine, of the fingers $g g'$, the cross-head f , shaft e , a cam and shaft for giving motion to the shaft e , connecting-rod, and adjustable crank and pin for varying the extent of motion given to the fingers, substantially as set forth.
- 45 8. The combination, with the fingers $g g'$, cross-head f , and shaft e , of the spring h , to press one finger toward the other, the tubular shaft d' , and crank-arm d'' , acting upon the spring h , and mechanism, substantially as specified, for giving motion to the respective parts 50 to rotate the bolt-rod and then to relieve the pressure of the fingers upon the same during the return movement, substantially as set forth.
9. The combination, with the holding and forging dies in a bolt-machine, of the fingers $g g'$, the cross-head f , and shaft e , the hook n , and

latch n' , the spring h , tubular shaft d' , and crank-arm d'' , and mechanism for giving motion to the respective parts, substantially as and for the purposes set forth.

10. The combination, with the holding and forging dies, of the cam D' , shaft a , tubular shaft b , arms at the ends of the respective shafts, shaft e , tubular shaft d' , and the crank-arms and connecting-rods, the cross-head f , fingers $g g'$, the spring h , to close the fingers, and arm d'' , for pressing back the spring, the hook n , and the spring r , for opening the fingers, and the latch n' upon the holding-jaw H' , substantially as set forth.

11. The combination, with the holding and forging dies, of the fingers $g g'$ and the mechanism, substantially as specified, for moving the same, the spring h , for pressing the fingers upon the bolt-rod, the treadle and lever for pressing back the spring, the hook n , latch n' , and spring r , substantially as set forth.

12. The combination, with the holding and forging dies, of fingers for giving a partial rotation to the bolt-rod, the connections, and a crank-pin and a crank-arm in which the pin is adjustable by a screw and mechanism for moving the crank and its pin, whereby the extent of motion given to the bolt-rod is varied by adjusting the crank-pin, substantially as specified.

13. The dies containing recesses for gripping the bolt-rod and flat surfaces for forging up the sides of the head, and a plunger for applying pressure endwise of the rod or bolt, in combination with fingers acting in opposite directions and at opposite sides of the bolt-rod to give to such rod a partial rotation between each stroke of the jaws that forge the polygonal head, substantially as specified.

14. The dies containing recesses for gripping the bolt-rod and flat surfaces for forging up the sides of the head, and a plunger for applying pressure endwise of the rod or bolt, in combination with automatic mechanism acting at opposite sides of the bolt-rod for giving to such rod a partial rotation between each stroke of the jaws and forging the polygonal head, substantially as set forth.

Signed by us this 4th day of December, 1885.
